ATTORNEY

UNITED STATES PATENT OFFICE

HOWARD AVERY FLAGGE, OF NORFOLK, VIRGINIA

PISTON OIL SHIELD

Application filed September 5, 1928. Serial No. 304,014.

This invention relates to piston shields for gasoline engines.

In the usual engine operating under the explosive principle wherein a piston is used to compress the mixture of gasoline and air and then to receive the impulse of the explosion the underside of the top of the piston becomes quite hot. Oil is splashed up against the heated underside of the piston top where 10 it carbonizes sometimes forming an incandescent cake on the under surface of the piston head. This carbonization increases the heat of the piston and breaks down the oil so that its lubricating powers as well as its cooling powers are much reduced.

One of the objects of this invention is to provide means to prevent carbonization of the oil on the underside of the piston head. Another object of the invention is to provide 20 means for prolonging the useful properties of the lubricating oil in the motor.

Still another object of the invention is to prolong the life of a gasoline motor.

Referring to the drawings:

25 Figure 1 is a sectional view of a piston having a shield therein embodying the principles of my invention.

Figure 2 is a cross sectional view along the line 2, 2, of Figure 1 of the shield.

30 Figure 3 is a bottom plan view of the shield.

Figure 4 is a modified plan view showing a modified form of shield in plan view prior to being bent to fit the inside of the piston.

35 Figure 5 is a sectional view of a piston wherein the modified form of shield is shown and wherein the shield is supported by legs or channels formed in the interior of the piston.

40 In carrying out my invention, I propose to provide a shield 1 for piston 2. Such shield 1 may be formed as shown in Figures 1 and 2 of a single piece of metal having cutout portions 10 to accommodate the wrist pin bosses

45 3. Shield 1 is sprung into place and is in contact with the inside walls of piston 2 only adjacent the mouth of the cup shaped shield 1, that is, only a small portion of the shield near the rim is in contact with the inside 50 walls of piston 2. If desired, the shield can

be secured to the skirt of piston 2 by welding or by bolts 11, although such is not required since once the cup is snapped into place and the connecting rod positioned it is impossible for the shield 1 to become dislocated. 55 I further propose to provide an asbestos gasket 5 between the shield 1 of the top of the piston 2 to prevent contact between the top of the shield 1 and the underside of the piston head 2. Where a sufficient air gap is possible, the heat insulating gasket 5 may be dispensed with. In certain engines the cup form of shield 1 is difficult to insert and the form shown in Figure 4 or modification thereof must be used. In the modified form the 60 shield 1' is formed from a Maltese cross having two of the arms of the Maltese cross cut out to accommodate the wrist pin bosses 3. The arms of the Maltese cross are bent to conform to the inside of piston 2 and can be 65 secured in place by welding or by bolts or by feet, lugs or channels as shown in Figure 5, reference numeral 6, 7. A gasket 5 of heat insulating material can also be used as shown in Figures 4 and 5. 70

It will thus be seen that I have invented a piston shield of simple construction and of light weight wherein carbonization upon the undersurface of the piston head is prevented and the temperature of the oil is not raised 75 up to the carbonization point as the shield is only in contact with the lower portion of the skirt of the piston. The skirt of the piston being relatively cool as compared to the piston face and hence transmits less heat to the shield which in turn transmits less heat to the oil.

It will be further seen that a motor utilizing my invention will function more efficiently.

What I claim is:

1. In a motor a piston, bosses in the interior of said piston for the wrist pin bearings, a shield in said piston having cut out portions for said bosses to extend through, the bottom edge of said shield only contacting with the interior of said piston at its lower portion and means for securing at the lower portion said shield within said piston. 95

2. In a motor a piston, bosses in the interior of said piston for the wrist pin bear- 100

ings, an oil shield in said piston having cut out portions for said bosses to extend through, said shield having a skirt extending below said bosses, means for securing said skirt to said piston and means for heat insulating the upper portion of said shield.

3. In a motor piston, a shield formed from sheet metal in the shape of a Maltese cross having two of the arms of the cross with 10 U-shaped cutout portions to fit over and around the bosses within the piston, said shield forming a cup shaped chamber within said piston when inserted, the bottom edges contacting with the lower portion of the sides 15 of said piston to prevent the passage of oil past the shield and means for insulating the top of said shield from the top of said piston.

HOWARD AVERY FLAGGE.
